(57) **CLAIM**

The ornamental design for a tapered computer desk, as shown and described.

DESCRIPTION

FIG. 1 is a perspective view showing the new design; FIG. 2 is a side view thereof; the opposite side being a mirror image thereof; and,

FIG. 3 is a bottom view thereof.

The surfaces that are not shown are merely plain and/or do not include any ornamentality are not illustrated in the drawing disclosure.

The broken lines are for environmental purposes only and form no part of the claimed design.
